FIG-2

FIG-4

FIG. 5

FIG. 6

FIG. 7

FIG. 1 is a perspective view of an unit embodying this invention with a fluorescent tube illustrated in dotted lines;

FIG. 2 is a side elevation of this unit illustrated in FIG. 1, with fluorescent tubes and large structures illustrated in dotted lines;

FIG. 3 is a bottom plan view of this unit illustrated in FIGS. 1 and 2;

FIG. 4 is a top plan view of this unit;

FIG. 5 is a side elevational view of a further embodiment of my design with fluorescent tubes and lamp structure indicated in dotted lines;

FIG. 6 is a top plan view of the unit illustrated in FIG. 5; and

FIG. 7 is a bottom plan view of the illustrated in FIG. 5.

Structures indicated in dotted lines form no part of our design and are presented merely to illustrate relationships

with structures with which units embodying our invention normally will be associated.

The tubular shade-supporting element is broken away in FIGS. 2 and 5 for convenience of illustration.

We claim:

The ornamental design for a circular fluorescent unit for lamps and the like, as shown and described.
